(57) CLAIM

The ornamental design for a neck towel for hairstyling, as shown and described.

DESCRIPTION

FIG. 1 is a perspective of a neck towel for hairstyling showing my new design in use;

FIG. 2 is another perspective view thereof, showing the neck towel in use; and,

FIG. 3 is a top plan view of the neck towel.

The broken lines in FIGS. 1 and 2, showing the design in use and representing the unclaimed portions of the design, are for illustrative purposes only and form no part of the claim.

1 Claim, 3 Drawing Sheets

FIG. 3
